(57) **CLAIM**

The ornamental design for a drill tie stake, as shown and described.

DESCRIPTION

FIG. 1 is an upper front right perspective view of the novel drill tie stake.

FIG. 2 is an enlarged perspective view of the blade head of the drill tie stake of FIG. 1.

FIG. 3 is a side view of the blade head of FIG. 2 along arrow 1B.

FIG. 4 is an enlarged view of a burr edge on the blade head of FIG. 3.

FIG. 5 is a lower rear left perspective view of the drill tie stake of FIG. 1.

FIG. 6 is an upper side view of the drill tie stake of FIG. 1.

FIG. 7 is a lower side view of the drill tie stake of FIG. 1.

FIG. 8 is a right side view of the drill tie stake of FIG. 1.

FIG. 9 is a left side view of the drill tie stake of FIG. 1.

FIG. 10 is rear end view of the drill tie stake of FIG. 1; and, FIG. 11 is a head end view of the drill tie stake of FIG. 1.

The dashed lines in FIGS. 2 and 11 represent a soft curve in the surface of the article and do form part of the claimed design.

1 Claim, 6 Drawing Sheets
